Des 760

2-12-1856

Lawrence Johnson, of Philadelphia, Pa.
Letters Patent No. 760, Dated Feb. 12. 1856.

Des. 760

The schedule referred to in these Letters Patent, and making part of the same.

To all whom it may concern,

Be it known that I, Lawrence Johnson of the City of Philadelphia, & State of Pennsylvania, have invented or produced a new & original design for printing-type, & I do hereby declare that the following is a full, & exact description of the same, reference being had to the accompanying printed specimen.

My design consists in forming on the printing face of type, such interstices & projections that the upper portion of each letter of the alphabet, printed from said type, shall have a colored ground with white stars & the lower portion of each letter has alternate white & colored stripes.

On reference to the printed specimen which forms a part of this specification,

Fig 1. represents a series of letters exhibiting impressions from the type, as arranged to print my design in one color with white stars & stripes.

Fig 2. Impressions of the same design as fig 1. but produced from type arranged to print in two different col-

ors, also with white stars & stripes.

I do not desire to confine this design to the exact form or size of letter shown, nor to the number of stars, or to the color of the ground.

But what I claim & desire to secure by Letters patent, is - the forming on the face of printing type such figures, that the letters printed therefrom, shall represent in the upper portion of each letter a colored ground with white stars, & in the lower portion, alternate white & colored stripes, substantially in the manner shown.
